CLAIM

The ornamental design for a power connector, as shown and described.

DESCRIPTION

FIG. 1 is a front perspective view of a power connector according to an embodiment of the new design;

FIG. 2 is a rear perspective view thereof;

FIG. 3 is a front view thereof;

FIG. 4 is a rear view thereof;

FIG. 5 is a right-side view thereof;

FIG. 6 is a left-side view thereof;

FIG. 7 is a top view thereof; and,

FIG. 8 is a bottom view thereof.

(Continued)

In these drawings, the solid lines illustrate the claimed ornamental design. The broken lines illustrate portions of the power connector that form no part of the claimed design.
